(57) CLAIM

The ornamental design of a barbecue grill side shelf with toolholders, as shown and described.

DESCRIPTION

FIG. 1 is a top plan of our new barbecue grill side shelf with toolholders showing my new design;
FIG. 2 is a bottom plan view thereof;
FIG. 3 a front elevational view thereof;
FIG. 4 is a rear elevational view thereof;
FIG. 5 is a left side elevational view thereof; and,
FIG. 6 is a sectional view taken along lines 6—6 in FIG. 1.
